Primary Examiner — Stacia Cadmus(74) *Attorney, Agent, or Firm* — RatnerPrestia(57) **CLAIM**

The ornamental design for a wheel for a motor vehicle, as shown and described.

DESCRIPTION

FIG. 1 is a perspective view of a wheel for a motor vehicle; FIG. 2 is a side elevation view of the wheel; and,

FIG. 3 is a front elevation view of the wheel.

The broken line showing of the center hole in the central hub area is included for the purpose of illustrating environment and forms no part of the claimed design.

1 Claim, 2 Drawing Sheets(56)
